[73] Assignee: **NCR Corporation**, Dayton, Ohio

[57] **CLAIM**

[**] Term: **14 Years**

The ornamental design for a peripheral cabinet for NCR 587X terminals, as shown and described.

[21] Appl. No.: **69,982**

DESCRIPTION

[22] Filed: **Apr. 21, 1997**

FIG. 1 is a right front perspective view of a peripheral cabinet for NCR 587X terminals showing my new design, the undisclosed bottom and rear and not part of the claimed design; and,

[51] LOC (6) Cl. **99-00**

FIG. 2 is a right side elevational view thereof, the undisclosed left side is not part of the claimed design.

[52] U.S. Cl. **D99/43**

The broken line showing of NCR 587X terminal in FIGS. 1 and 2 is for illustrative purposes only and forms no part of the claimed design.
